UNITED STATES PATENT OFFICE.

HARRY C. LYONS, OF NEW YORK, N. Y.

LIQUID-DISPENSER.

1,272,688.

Specification of Letters Patent. Patented July 16, 1918.

Application filed April 28, 1917. Serial No. 165,131.

To all whom it may concern:

Be it known that I, HARRY C. LYONS, a citizen of the United States, and a resident of the borough of Manhattan, city, county, 5 and State of New York, have invented certain new and useful Improvements in Liquid-Dispensers, of which the following is a specification.

My invention relates to means for dispensing liquids containing constituents of 10 different specific gravities, as set forth in Letters Patent No. 1,139,129, issued to me May 11, 1915, and in Letters Patent No. 1,181,783, issued to me May 2, 1916.

15 The object of the present invention is mainly to simplify and cheapen the apparatus, and render it more adapted to the exigencies of quick and frequent cleansing, especially when used for the dispensing of 20 milk, in which case sanitation is of vital importance. The invention consists in the specific construction and arrangement of parts herein described and claimed,—a distinctive feature being the elimination of 25 mixing chamber and valves and the connecting of the dispensing faucet directly with the floatable drain duct and with the main reservoir, thereby preventing possibility of 30 back flow of the heavier liquid constituent into the floatable drain duct when the faucet is closed. Hence the relative proportions of the heavier and lighter liquid constituents are always the same in the admixture 35 dispensed, be the quantity withdrawn small or large,—the operation being more direct and positive.

In the accompanying drawings,

Figure 1, is a top view of my improved liquid dispenser, with the cover removed; 40 Fig. 2, is a central vertical sectional elevation thereof, parts being broken away;

Fig. 3, is a sectional detail taken at right angles to Fig. 2, showing the coupling between the faucet and the floatable drain 45 duct;

Fig. 4, is an elevation of the inner end of the faucet plug shown in the preceding figures;

Fig. 5, is a view like unto Fig. 2, showing 50 a modification;

Fig. 6, is a section taken upon plane of line 6—6, Fig. 5.

The dispensing receptacle or reservoir D, is preferably although not necessarily of 55 cylindrical shape in horizontal cross section, and is inclosed ordinarily in an outer shell

or casing D', of sufficient size and capacity to contain a packing of ice, or a packing of non-conducting material, as may be found most expedient in adapting the apparatus 60 to the character of the liquid constituents to be dispensed,—it being understood that I herein by way of illustration describe the apparatus as adapted to the storage and dispensing of milk, without limiting myself 65 to that specific purpose, to which however it is especially adapted. The reservoir D, is provided with a removable cover d, and is otherwise adapted to meet the requirements 70 of practical use.

In Figs. 1, 2, 3, and 4, the threaded inner end of the dispensing faucet-casing screws into a sleeve or bushing d², extending through the walls of the reservoir D, and casing D', and through the intervening 75 space; or connection is otherwise made with the interior of the reservoir D. In the modification shown in Figs. 5, and 6, the faucet C, is positioned mainly in the space between the bottom of the reservoir D, and the bottom of the casing D'. In either arrangement the casing c, of the faucet is formed with outlet ports i, i', which communicate with the interior of the reservoir D,—the one outlet i, opening directly thereinto, 80 while the other i', communicates with the interior of the reservoir through the medium of the floatable drain duct F. Both outlets i, i', are adapted to communicate with the interior of the hollow plug c', 85 when the latter is turned so that its port or ports (as the case may be) coincide therewith, and as shown in both Figs. 2 and 5, of the drawings, so as to afford a common means for the simultaneous discharge from 90 the reservoir of both liquid constituents. In fact the hollow plug in this case, and in either arrangement shown, becomes the mixing and discharge chamber, and the only one, thus obviating the necessity for the separate mixing chamber, valves, etc., heretofore provided as in the Letters Patent here- 100 tofore referred to.

The hollow plug c', of the discharge cock C, is preferably of conical form, and is held to its seat in its casing c, by an expansion spring c², interposed between said casing c, and a nut c³, screwing onto the end of the plug c', thus insuring a close fit, and preventing communication between the outlets 110 i, i', when the plug is turned to close the same.

The floatable drain duct F, is pivotally supported upon a fulcrum-elbow e, formed with a tubular coupling member e', one end of which is adapted to fit in a socket c⁴, 5 formed for its reception in the casing c, of the faucet C,—the passage in said tubular coupling member e', communicating directly with the outlet i'.

The lateral extension e², of the elbow e, 10 constitutes the trunnion upon which the lower end of the floatable drain duct F, is pivotally supported, as shown more particularly in Fig. 6, by reference to which, and to Figs. 1 and 3, it will be seen that said 15 lower end of the floating drain duct F, is formed with a cross sleeve or T f, which fits over said lateral extension e², of the fulcrum elbow e and is held thereon by a cap screw e³, engaging with the externally threaded end 20 of the aforesaid lateral extension e², of the fulcrum elbow e. Said lateral extension or trunnion e², is formed with a port e⁴, (Fig. 6) of shape and area sufficient to maintain continuous communication between the lower 25 end of the float drain duct F, and the outlet passage through the elbow e, to the port i', which delivers the lighter liquid constituent to the hollow plug c', of the dispensing faucet C.

30 The free end of the coupling member e', of the fulcrum elbow e, simply fits snugly within the socket c⁴, of the faucet casing c, so as to be readily detachable therefrom by simply pulling said coupling member e', 35 out of said socket c⁴, thus freeing the fulcrum elbow e, and float drain duct F. Then, by the removal of the screw cap e³, the fulcrum extension e², may be readily withdrawn from the cross T f, of the float drain 40 duct F, so that all the parts and joints are rendered readily accessible and cleanable.

A float f², of any desired construction or configuration is attached to the floatable-drain-duct F, at or near its upper extremity 45 in such manner as to maintain the mouth or inlet f³, of the said duct F, slightly below the level of the liquid in the reservoir D. Hence, obviously the upper strata of liquid in the receptacle D, will always have 50 access to said drain duct F, no matter what the height of the liquid level may be, nor how much it may vary, vertically considered, as related to the outlets i, i'.

The use of a mixing chamber and valves 55 in connection with the outlets i, i', as set forth in the above mentioned patents is entirely feasable and satisfactory in so far as

operativeness in concerned, but where milk is the liquid dispensed and the apparatus has to be frequently cleaned and scalded 60 throughout, the mixing chamber, valves, etc., render the problem of perfect sanitation difficult and expensive. Furthermore the initial cost thereof is objectionable 65 where a simple, cheap dispenser is a desideratum.

I not only overcome these objections to my old form of dispensing apparatus by forming the outlets i, i', directly in the faucet casing itself, but I also obviate all danger of 70 the heavier liquid constituent rising in the floatable duct tube since the mixing chamber is eliminated entirely, the constituents of the liquid dispensed meeting only in the hollow discharge plug of the faucet, 75 which when closed effectually closes both outlets i, i', the one from the other, so that there can be no communication between them, and no back flow into the floatable drain duct.

What I claim as my invention and desire to secure by Letters Patent is,

1. A mixing faucet for dispensing liquids of different specific gravities, comprising a casing having a plurality of discharge passages and a faucet plug having a central bore and an inlet and fitting in said casing capable of being turned to communicate with the passages in the casing, a reservoir in which said casing is removably secured 90 with its inner end substantially flush with the wall thereof, and a floatable drain duct having a tubular coupling member at its lower end removably fitting within one of the discharge passages of the casing. 95

2. A mixing faucet for dispensing liquids of different specific gravities, comprising a casing having a plurality of discharge passages, and a faucet plug having a central bore and an inlet thereinto, said plug fitting in said casing and capable of being turned to communicate with the passages in said casing, a reservoir in the wall of which said casing is removably inserted from the exterior with its inner end substantially 100 flush with the inner wall of the reservoir, a floatable drain duct and a fulcrum elbow supporting said duct and having a tubular coupling member removably supported in one of the discharge passages of said casing. 105
